UNITED STATES PATENT OFFICE.

ERASTUS WOODWARD, OF SOMERVILLE, MASSACHUSETTS, ASSIGNOR TO THE
WATERS WRAPPING AND MAILING MACHINE COMPANY, OF PORTLAND,
MAINE.

ADDRESS-PRINTING MACHINE.

SPECIFICATION forming part of Letters Patent No. 434,412, dated August 12, 1890.

Application filed November 5, 1889. Serial No. 329,379. (No model.)

To all whom it may concern:

Be it known that I, ERASTUS WOODWARD, of Somerville, county of Middlesex, State of Massachusetts, have invented an Improvement in Address-Printing Machines, of which the following description, in connection with the accompanying drawings, is a specification, like letters on the drawings representing like parts.

10 This invention has for its object to improve that class of machines employed for printing addresses upon a strip, one address following another.

One part of my invention relates to means 15 for feeding the paper strip and for punching a series of holes therein, to be thereafter entered by a feeding finger or device when the said printed strip is being used in a machine for wrapping newspapers or other packages or articles for the mail, the said strip at such time being cut off transversely to leave pieces each containing an address printed on it. The strip referred to may be of any desired width and be gummed or not. The paper on which the addresses are printed may be wide enough to be used for a newspaper-wrapper, or it may be just wide enough to take the addresses and be thereafter applied to the wrapper.

20 The machine described in United States Patent No. 408,202, heretofore granted to me, shows the use of a narrow strip of the kind referred to.

The machine herein to be described contains pulling-off mechanism (shown as rolls) 25 which acts upon the strip of paper upon which separate addresses are to be printed, the said mechanism pulling off from the delivery drum or roll an amount of paper in excess of that actually needed or taken away by the feed-rolls which feed the strip under the impression pad and punch, the formation of slack in the paper strip by the pulling-off mechanism obviating the necessity of the feed-rolls acting upon the paper to turn the delivery roll or drum containing the roll of paper, for it will be noticed that the strain on the paper to rotate the said drum or roll varies as the diameter of the roll of paper being printed 40 decreases. The strip having addresses printed upon it is wound up upon a receiving-roll,

which is driven frictionally or in such manner that the rotation of the said receiving-roll ceases whenever the printed strip between it and the feed-rolls is taken up.

55 The machine herein to be described has a punch and punch plate or die, so that holes are punched in the strip, one for each address, and at a short distance from its edge, the said holes being herein shown as so located 60 in the said strip as to come between the separate addresses. The galley containing the type is fed intermittently under the moving paper and under an impression-pad, and the galley is provided with a projection, whereby 65 when it reaches the end of its movement in one direction a locking device which is depended upon to keep the machine in rotation is acted upon by the galley and rolls to effect the stopping of the machine, and especially 70 of the feeding mechanism and the impression-pad and punch.

Figure 1, in front elevation, represents an addressing-machine embodying my invention. Fig. 2 is a right-hand end elevation thereof. Fig. 3 is a left-hand end elevation. Fig. 4 is a detail to be referred to, it showing the means for actuating the impression-pad and the punch, together with part of the frame-work below the impression-pad, and the galley and 80 part of the stop mechanism to be described. Fig. 5 is a detail showing part of the frame-work with the galley in place and part of the stop mechanism. Fig. 6 is a detail showing one side of the cam represented in Fig. 4. 85 Figs. 7 and 8 are details referring to the stop mechanism and to the belt-shipping mechanism. Fig. 9 is a detail showing the punch-block and stripper detached. Fig. 10 shows a piece of paper having addresses printed thereon and punched with holes, and Fig. 11 is a detail referring to the means employed for adjusting the vertical position of the impression-pad; Fig. 12, a detail showing the links f^6 and b^6 , and Fig. 13 details of the locking device. 90

95 The frame-work, composed essentially of the post or upright A, a horizontal bed A' A^x, uprights A², A³, and A⁴, is and may be of suitable shape to support the bearings for the working parts. The portion A^x of the frame-work is made as a horizontal shelf having an upright guiding-edge a at its rear side. 100

The galley B rests upon this shelf and is moved intermittently thereon by mechanism to be described. The galley is and may be of usual construction, it containing properly 5 set up and keyed therein type, as b, to represent a name and post-office address, &c., the said addresses being properly spaced and separated, the galley being fed by means of a feeding mechanism which, as shown, is made 10 to engage the type b, as will be described.

The main shaft B' of the machine has fast on it near its outer end a disk B², on the hub of which is pivoted at b' a dog B³, which is acted upon by a spring b², surrounding a rod 15 or pin b³, jointed at one end to the said dog and extended through a portion of the hub of the wheel B². The wheel B² serves as a brake-wheel and is acted upon at the proper times by a brake B⁴, connected to a sleeve B⁵, 20 having an arm B⁶, which by a link B⁷ is attached to an arm B⁸ of a rock-shaft B⁹, extended to the front of the machine and provided with an arm B¹⁰, a spring B¹² normally 25 acting to keep the brake pressed against the brake-wheel, the said arm B¹⁰ enabling the said rock-shaft to be turned by hand.

Loose on the shaft B' is a belt-pulley C, having at one side (see Fig. 2) a projection C', which when in engagement with the dog 30 B³ effects the rotation of the main shaft, but this dog B³ may be disengaged from the said pin by the arm C², connected to the sleeve B⁵, as will be described.

The hub of the pulley C, which, it will be 35 understood, is driven from some usual counter-shaft and which runs even when the machine proper is stopped, is scored to receive a belt C³, which is extended over a pulley C⁴ on a shaft C⁵, having a second pulley C⁶, (see Fig. 3,) over which is extended a cross-belt C⁷, which is also extended over a pulley C⁸, fast 40 on a shaft C⁹, to which is attached the distributing-roll C¹⁰, the said shaft C⁹ having upon it a cam-hub C¹², the groove of which 45 receives a roller or other stud C¹³ on a finger attached to a swinging yoke C¹⁴, in which said shaft has its bearings, the said yoke being pivoted at its inner end upon the upright A². The frame-work has upon it a stud a', which 50 receives the journal of the inking-roll a², with which roll co-operates a second inking-roll a³, the shaft of which turns in a swinging yoke a⁴ pivoted at a⁵, the journals of the two rolls being connected by a spring a⁶, as represented 55 in Fig. 1.

The main shaft B' has fast upon it a feed-cam D to actuate the galley-feeding mechanism, the said cam, as herein shown, being provided at one side with a suitable cam-groove, the shape of which is best shown in Fig. 6, the said cam-groove, as herein represented, receiving a roller or other stud of an arm D', attached to a rock-shaft D², upon the forward end of which is mounted loosely and in an adjustable manner the feed-actuating lever D³.

To effect the adjustment of the lever D³, I

have secured to the shaft D², immediately behind the said lever, a hub D⁴, having a forked arm or upright in which is placed a screw D⁵, 70 provided with a suitable thumb-nut, the said screw passing through an ear D⁶, (shown by dotted lines in Fig. 4,) connected to and extended backward from the upper end of the lever D³. A pin or projection 40 at the lower 75 end of the lever D³ enters a notched ear a⁷ of a feed-bar a⁸, fitted to slide in suitable guides next the part a of the table, the said slide having a feed-dog a⁹ pivoted thereto at a¹⁰, the forward end of the said feed-dog having a 80 projection, as best represented in Fig. 5, to go into the space between the type b indicating definite addresses, the said dog by engaging the type feeding the galley the proper distance. The feed-dog is normally kept pressed 85 toward the galley by means of a spring a¹², adjustment of the screw D⁵ providing for a shorter or longer throw of the bar carrying the dog, such adjustment providing for the varying spaces between the type in the galley used.

The outer side of the galley is acted upon at suitable points by means of one or more rolls c on an arm c' of a vertical rock-shaft having at its lower end an arm c², acted upon 95 by a spring c³, the other end of which is attached to some fixed part of the frame, the said rolls keeping the galley up against the guiding-edge a.

When the machine is running regularly, 100 the rock-shaft B⁹ is turned in a direction to keep the brake B⁴ off from the brake-wheel and the arm C² out of the path of movement of the dog B³, and the said rock-shaft is kept in such position by means of a locking mechanism consisting, essentially, of a latch c⁴, attached to the lower end of a vertical rock-shaft c⁵, extended through the bed A' and having a finger c⁶. The latch c⁴, as herein shown, has attached to it a spring c⁶, which 110 normally serves to keep said latch engaged with an arm c⁷ on the said rock-shaft B⁹. When the galley arrives at the end of its stroke, a projection c¹⁰, (see Fig. 5,) mounted just behind the last type to be printed from in 115 the galley, strikes the finger c⁶ and turns the shaft c⁵, thus releasing the arm c⁷ of the shaft B⁹ and permitting the spring B¹² to throw the brake against the brake-wheel and the arm C² up into position to effect the disengagement 120 of the dog B³ from the projection C' on the loose driving wheel or pulley C.

The machine may be stopped at any time by the operator engaging the arm c⁸ by hand.

The main shaft has fast upon it a pinion E, which engages an intermediate toothed gear E' on a shaft E², the said shaft containing a pinion e, and alongside of it a belt-pulley e'. The belt-pulley e' receives over it, as 130 herein shown, a belt e², which is extended over a wheel e³, mounted loosely upon a shaft e⁴, the said shaft having fast upon it a disk e⁵, between which and one side of the hub of

the said pulley e^3 is a suitable friction device e^6 , preferably a leather washer. The shaft e^4 also has mounted upon it the take-up drum or roll e^7 , it being herein shown as retained 5 upon and to rotate with the said shaft by means of a pin e^8 at the inner side of a hub e^9 attached to the said shaft by means of a set-screw e^{10} . A spiral or other spring e^{12} , (see Fig. 2,) located between the bearing e^{13} 10 for the said shaft and the hub of the pulley e^3 , acts to keep the hub of the pulley pressed toward the leather washer e^6 and the disk e^5 with a measured friction. In this way it will be seen that the rotation of the pulley 15 e^3 , although being constant, does not at all times rotate the shaft e^4 , upon which it is mounted, and thus rotate the take-up reel e^7 . The friction device between the wheel e^3 and the disk e^5 is provided in order that the rotation of the reel e^7 may be stopped whenever 20 the paper strip F (represented by dotted lines) has been taken up or the slack therein wound up beyond the feed-rolls $f f'$.

The feed-roll f is mounted upon a shaft f^2 , 25 provided with a suitable ratchet or other wheel f^3 , (see Fig. 2,) engaged by a suitable pawl f^4 on the pawl-lever f^5 , pivoted preferably on the shaft f^2 , the said pawl-lever deriving its motion from a link f^6 , pivoted to 30 the link f^8 , to be described, the latter link embracing a crank-pin f^9 upon a disk f^{10} , secured to the front end of the shaft B' , the rotation of the feed-roll f being intermittent. The roller f' is secured to a shaft f^x , rotating 35 in the lower end of arms f^{12} , pivoted at f^{13} on the upright A^4 , the roll f' being held against the paper on the roll f by a suitable spring f^{14} . The shafts f^2 and f^x at their inner ends 40 are provided each with a suitable pinion, which mesh together, thus causing the said shafts to rotate in unison and take the paper strip F (shown by dotted lines) from the addressing and punch mechanism, to be herein-after described. The link f^8 is jointed to a 45 stud-screw g , secured to a carrier or bar g' , and as the shaft B' is rotated the said carrier or bar is reciprocated between suitable gibs, forming a guide therefor.

The carrier or bar g' , as herein represented, 50 has at its lower end a projecting block g^2 , having a suitable vertical groove or guideway therein to receive the shank g^3 of the impression-pad g^4 , it being suitably cushioned at its lower end to strike upon the paper F , lying 55 upon the type b of the galley, the said type being properly inked by the inking-rolls $a^2 a^3$ as the galley passes under them.

The shank of the impression-pad is represented as provided at its upper end with an 60 ear 42 , (see Figs. 4 and 11,) having a hole in which is fitted loosely a screw g^6 , the lower end of which is threaded and fitted to enter a threaded opening in the block g^2 , attached to the carrier g' . The screw g^6 has upon a 65 threaded portion thereof a fast collar 41 , on which rests the ear 42 . The screw g^6 is grooved just above the said ear to receive a suitable

spline or projection (see Fig. 11 in section) at the inner side of a loose collar 43 , so that by turning the said collar the screw may be rotated and turned up or down in the said block. 70

To permit the impression-pad to stop just before the bar g' completes its descent, or to strike a yielding blow upon the paper lying 75 on the type of the galley, I have surrounded the screw g^6 above the collar 43 with a spiral spring 44 , the upper end of which is acted upon by a nut 45 . In this way when the impression-pad strikes the paper or type, the 80 ear 42 being then under the collar 43 , the spring 44 yields so as to avoid striking a hard or solid blow.

As herein shown, I have secured to the projection g^2 by a suitable screw g^{10} (see Fig. 4) 85 a holder h , in which is secured a punch h' . The bed A^x has secured to it immediately below the punch a stripping-plate h^2 , provided with a hole h^3 , down through which the punch passes before passing through the paper strip 90 F , a punch-block h^4 (shown best in Fig. 9) lying just below the stripping-plate h^2 and the paper, the said punch entering a hole in the said punch-block. The pinion e engages a toothed gear h^5 , fast on a shaft h^6 , to which 95 is secured the pulling-off wheel or device h^7 , the co-operating wheel or device h^8 to take the strip of paper to be addressed from the roll of paper on the roll or reel F' being fast upon an arm h^9 , pivoted at h^{10} on the upright 100 A^2 , the roll h being kept pressed against the paper on the roll h^7 by means of a spring h^{20} . (Shown by dotted lines in Fig. 1.) The inner ends of the shafts carrying the said wheels h^7 105 h^8 are provided with like pinions h^{12} , (both shown in full lines in Fig. 3 and one by dotted lines in Fig. 1,) so that the said shafts rotate in unison and pull off the paper strip F from the delivery-roll F' at a constant speed, notwithstanding the constantly-decreasing diameter of the paper on the said roll. The paper pulled off from the delivery-roll in excess of the quantity demanded or the quantity taken away by the feed-rolls $f f'$ is accumulated in loop form, as represented at the 110 left of Fig. 1, the said loop representing slack paper resting in a suitable guide or chute m , having at its lower end, preferably, a suitable top plate, as m' , the paper to be printed upon being delivered upon the type b of the galley 115 under the impression-pad.

The bed A^x will have a supporting-plate m^2 , over which the printed strip travels on its way to the feed-rolls, the said plate (but partially shown in Fig. 5) keeping the printed 120 part of the strip from coming a second time against the type.

The strip may be gummed and dried at one side, if desired, before it is put through the machine to have the addresses printed upon it. 125

I do not desire to limit my invention to the exact location of the punch with relation to the impression-pad, for in practice to produce a rapid-working machine it is only neces-

sary that the said punch and the said impression-pad come down upon the paper strip, whatever may be its width, at substantially the same time, so as not to interfere any longer than possible with the intermitting action of the feed-rolls. Neither do I desire to limit my invention to the exact means shown for actuating the impression - pad and the punch, as I may use any other well-known equivalent devices.

It is obvious that the width of the strip upon which the addresses are printed may be of greater or less width, a receiving roll or drum and a delivery roll or drum being used of suitable width for the strip.

In case of very wide strips—such, for instance, as used for newspaper-wrappers—the bed A^x will be correspondingly widened. The bed A^x has at its under side, near its left-hand end, as shown in Fig. 1, a rock-shaft n , having a yoke-shaped arm n' , which receives the journals of a roll n^2 , the surface of which may project up through a slot in the bed A' . This rock-shaft n has an arm n^3 , to which may be attached in any desired position a suitable weight or equivalent n^4 , and extending from the said rock-shaft in the opposite direction is an arm n^5 , which is acted upon by a lug 2 at the under side of the yoke C^{14} , before referred to, the weight of the said yoke and its attached parts on the arm n^5 being sufficient to counterbalance the weight n^4 and keep the periphery of the roll n^2 up into the slot in the bed A^x and slightly above it. In practice, when the galley is pushed into position from the left, as shown in Fig. 1, the under side of the galley acts upon the roll n^2 and pushes the said roll down sufficiently to turn the rock-shaft n and cause its arm n^5 to lift the yoke C^{14} sufficiently to remove the ink-distributing roll from contact with the two inking-rolls, for while the galley is being run through the machine and the inking-rolls are inking the type in the galley it is not desired to rub or work the distributing - roll against the inking-rolls. This lifting of the distributing-roll avoids much wear between the distributing-roll and the inking rolls; but as soon as the rear end of the galley travels beyond the roll n^2 the yoke C^{14} , being no longer supported, as described, falls sufficiently to permit the distributing-roll to meet the inking-rolls, and while a new galley is being put into place the rotation of the distributing-roll is continued, as before, in contact with the inking-rolls to properly distribute the ink thereon.

By the term "addressing-strip" I mean a strip of paper on which addresses are printed, the said strip being thereafter cut up into lengths, each length serving to address a paper or package for the mail.

The loose pulley with its projection, and the spring-pressed dog B^3 , constitute a clutch which when the acting parts are released enables the shaft B' to remain at rest.

I do not desire to limit my invention to the

exact devices shown between the locking device referred to and the clutch referred to, as instead I might employ other well-known equivalent devices.

I claim—

1. In a machine to print a strip of paper with a series of addresses, the following instrumentalities, viz.: an impression - pad, means to move it, a galley containing type, feeding mechanism to feed the said galley intermittingly, feeding mechanism to move the strip to be printed upon, and a punch and punch-block to form holes in the said strip, the said parts being and operating substantially as described.

2. The impression-pad, a carrier therefor, means to move the carrier, a feed-cam, its shaft, a galley having a projection, and means between the said feed-cam and the said galley to feed the latter, combined with a locking device actuated by the projection of the said galley, and means between the said locking device and the shaft carrying the feed-cam to arrest the rotation of the said cam as the galley completes its movement in one direction, substantially as described.

3. The impression-pad, a punch and punch-block, means, substantially as described, to move them, a galley having a projection c^{10} , a finger c^8 , and a connected locking device combined with feeding mechanism for the galley, and independent feeding mechanism for the strip to be printed, the said locking device being moved as the galley completes its feeding movement in one direction, substantially as described.

4. In a machine for printing addresses on a strip of paper, pulling-off mechanism, substantially as described, to act upon and pull the said strip from a drum or roll, and feeding-rolls to take the material delivered by the pulling-off mechanism, combined with a galley, an impression-pad, a carrier therefor, and with means to actuate the said galley and impression-pad carrier to operate substantially as described.

5. In an addressing-machine, pulling-off rolls to act upon and pull the paper strip from the drum or roll carrying it, a galley, means to feed it intermittingly, an impression-pad, a punch, means to actuate the said impression-pad and punch, and a punch-block, combined with feeding-rolls to take the paper from the pulling-off rolls and feed it under the impression-pad and punch and over the galley, substantially as described.

6. In an addressing-machine, pulling-off rolls to act upon and pull the paper strip from the drum or roll carrying it, a guide or chute m to support the slack paper, a galley, means to feed it intermittingly, an impression-pad, a punch, means to actuate the said impression-pad and punch, and a punch-block, combined with feeding-rolls to take the paper from the pulling-off rolls and feed it under the impression-pad and punch and over the galley, substantially as described.

7. In an addressing-machine, pulling-off rolls to act upon and pull the paper strip from the drum or roll carrying it, a galley, means to feed it intermittently, an impression-pad, 5 a punch, means to actuate the said impression-pad and punch, and a punch-block, combined with feeding-rolls to take the paper from the pulling-off rolls and feed it under the impression-pad and punch and over the 10 galley, and the plate m^2 , located above the galley, and means to wind up the printed strip, substantially as described.

8. The galley and feeding mechanism to move it, the shaft B', impression-pad carrier 15 and means to actuate it, combined with an impression-pad, and means to connect its shank in a yielding manner to the said carrier, substantially as described.

9. In a machine for printing addresses on 20 a strip, the shaft B', the loose pulley having a projection, the dog and spring, the impression-pad carrier actuated by the said shaft, the

impression-pad, feeding mechanism for the strip, the galley having a projection, means to actuate the galley, and a locking device actuated by the said galley, combined with the rock-shaft B⁹, having an arm c⁷, the arm C², and connecting devices between the said arm and the said rock-shaft to release the said dog from the said loose pulley when the locking device is moved to release the arm c⁷, substantially as described. 25 30

10. The galley, the feed-dog a⁹ to effect the feeding movement of the galley, the feed-bar, the lever D³, means to actuate it, and the 35 adjusting-screw D⁵, to operate substantially as described.

In testimony whereof I have signed my name to this specification in the presence of two subscribing witnesses.

ERASTUS WOODWARD.
